PIANO CASE

Wilbur M. Day, Kenwood, Ohio, assignor to D. H. Baldwin Company, Cincinnati, Ohio, a corporation of Ohio

Filed Sept. 24, 1963, Ser. No. 76,700

Term of patent 14 years

(Cl. D56—9)

The figure is a perspective view of a piano case showing my new design.

The dominant features of my design reside in the portion shown in full lines.

I claim:

The ornamental design for a piano case, substantially as shown and described.
